UNITED STATES PATENT OFFICE

126,393

DESIGN FOR A COIN OPERATED MOTION PICTURE MACHINE

Don Heyer, Hollywood, Calif.

Application August 27, 1940, Serial No. 94,648

Term of patent 7 years

To all whom it may concern:

Be it known that I, Don Heyer, a citizen of the United States, residing at 8851 Beverly Boulevard, Hollywood, in the county of Los Angeles and State of California, have invented a new, original, and ornamental Design for a Coin Operated Motion Picture Machine, of which the following is a specification, reference being had to the accompanying drawing, forming part thereof.

Referring to the drawing:

Figure 1 is a front elevational view of a motion picture machine showing my new design;

Figure 2 is a side elevation thereof; and

Figure 3 is a top plan view.

I claim:

The ornamental design for a coin operated motion picture machine, as shown.

DON HEYER,
